Patented Feb. 1, 1916.

UNITED STATES PATENT OFFICE.

WILLIAM L. NIEMANN, OF MOUNT OLIVE, ILLINOIS.

PEN-WIPER.

1,170,314.

Specification of Letters Patent.

Patented Feb. 1, 1916.

Application filed November 6, 1914. Serial No. 870,643.

To all whom it may concern:

Be it known that I, WILLIAM L. NIEMANN, a citizen of the United States, residing at Mount Olive, in the county of Macoupin and 5 State of Illinois, have invented certain new and useful Improvements in Pen-Wipers, of which the following is a specification.

This invention relates to pen wipers, and more particularly to that class of pen wipers 10 in which a ribbon or tape is provided on which to wipe the pen.

An object of the invention is to provide a casing having means disposed therein for wiping both the concaved and the convexed 15 sides of a pen point.

Another object of the invention is to provide a pen wiper which is in the form of a box having tapes or ribbons mounted therein for wiping the pen and to so construct 20 the box that the sides are removed, thus facilitating application of a new ribbon or tape.

A further object is to provide means for holding the tape so that a new piece of 25 tape will be positioned for operation when desired, and to provide means for tensioning the tape to hold the same in its operative position.

With these and other objects in view, the 30 invention consists in the novel features of construction, combination and arrangement of parts as will be hereinafter more fully described, illustrated in the accompanying drawings and claimed.

35 In the drawings:—Figure 1 is a perspective view of a pen wiper constructed in accordance with the invention; Fig. 2 is a longitudinal sectional view therethrough; Fig. 3 is a transverse section on the line 3—3 40 of Fig. 2.

In the preferred embodiment of my invention, I provide a casing comprising a base portion 1, end walls 2, and a longitudinally extending partition 3 which is located 45 centrally of said end walls, the sides 4 of the casing being removable and held in their relation to the end walls by means of overlapping portions formed on said end walls. A cover 5 is provided for the casing and 50 is provided with a depending flange 6 for engagement with the side and end walls to prevent the ready removal therefrom. Angled projections 7 are formed on the inner faces of the removable sides and are

adapted to support cushion rubber forms 55 8, the form carried by one of the members 7 being concaved on its outer face, and the other form convexed. The members 7 also serve to space the removable sides with respect to the partition 4. Tapes or ribbons 60 9 are adapted to be passed over the forms 8 so that when the door 10 of the cover is raised the concaved or the convexed side of the pen may be wiped on the tape which is passed over the respective concaved or convexed rubber form. In order to hold the tape or ribbon in slight tensioning engagement with the forms 8 and to provide for presenting new portions of the tape for use, I provide slotted studs 11 and 12, the studs 70 12 being passed through bearings formed on the outer faces of the removable sides and having the slots thereof adapted to receive the respective ends of the ribbon 9, so that by turning one of the studs, the tape will 75 be rolled over and off of the other stud, thumb gripping portions 13 being formed on the outer ends of the studs to facilitate the turning thereof. In order to hold the ribbon in tensioned engagement with the 80 forms 8, studs 14 are formed on the inner face of the removable sides and are adapted to support coil springs 15, one of the free ends of which engages the ribbon 9 while the other end is prevented against movement in one direction by means of a stud 16. 85

From the construction above described it will be seen that the studs 11 may be withdrawn and the ribbon 9 removed and a new ribbon inserted with but slight effort on the 90 part of the user of the device.

From the foregoing description taken in connection with the accompanying drawings, it is thought that the construction and operation of the device will be clearly understood, and while I have herein shown and described one specific form of my invention I do not wish to be limited thereto, except for such limitations as the claims may import.

I claim:—

1. In a pen wiper, the combination of a casing, a pair of studs mounted in said casing, a ribbon wound about said studs, a cushion member arranged between said 105 studs over which said ribbon is trained, the upper face of said cushion member being curved, substantially as described.

2. In a pen wiper, the combination of a casing, studs mounted in said casing, a ribbon wound about said studs, a cushion member arranged between said studs over which said ribbon is trained, means arranged exteriorly of the casing to rotate said studs and move said ribbon over said cushion member, a spring for tensioning said ribbon, the upper

face of said cushion member being curved, substantially as described. 10

In testimony whereof I affix my signature in presence of two witnesses.

WILLIAM L. NIEMANN.

Witnesses:

W. H. KLEIN,

A. E. FISCHER.
